MEANS FOR DRAFTING SHOE HEELS

George Clauising, Portsmouth, Ohio, assignor to
The Vulcan Corporation, Portsmouth, Ohio, a
corporation of Ohio

Application October 9, 1931, Serial No. 567,934

11 Claims. (Cl. 33—3)

My invention relates to means employed to determine the proper angles and design of a shoe heel from a last to be used in the manufacture of a particular style of shoe for which the heel is intended.

It is an object of my invention to provide a mechanical means for determining the degree of wedge of the heel of the last and the spring of the toe.

10 It is another object of my invention to provide a mechanical means for determining the degree of wedge of a heel of the last with a given spring of the toe and then to transfer these determined dimensions to a graphical chart, determining the 15 line of degree of wedge directly from the mechanical means so as to provide a pattern and a template to produce the desired heel.

Another object of my invention is to provide an 20 interchangeable and adjustable means for determining the outlines of different types of heels with a means for making a graphical representation from which the shoe heel can be completely designed, and which can be retained as a permanent record for duplication.

25 Another object is to provide a machine in which it is possible to set the parts thereof so that the heel height, and the degree of wedge and the toe-spring of a last can be measured directly for the purpose of designing a heel for a shoe.

30 Another object of my invention is to provide a chart to be used with the shoe heel drafting machine, and on which definite lines may be defined by placing the machine on the chart, for graphically outlining the pattern of the shoe last and 35 the position of essential contour determining points of a heel whereby to permit completion of the design of the heel which conforms to the particular style of shoes as indicated by the shoe last pattern outlined on the chart.

40 These and other objects will be more specifically pointed out in the description of a preferred embodiment of my invention as illustrated in the drawings, in which:

45 Figure 1 is a side elevation of the machine showing a last in position thereon.

Fig. 2 is a similar view of the machine, showing how the protractor is applied in order to determine the degree of wedge of the heel.

50 Fig. 3 is a similar view of the machine, showing the use of the protractor for determining the height of a heel.

Fig. 4 is a plan view of the machine.

55 Fig. 5 is a left end view of the base plate, legs and toe-spring plate.

Fig. 6 shows a chart that is to be used with the machine, showing the outline of a shoe last and two different styles, one in solid lines and the other in dotted lines, of heels that would be appropriate for a shoe made to that last. The heel shown in solid lines is a Cuban heel, and the heel shown in dotted lines is a Louis heel, there being two different lip lengths shown for this last named heel.

As shown in the drawings, I have provided a 10 measuring instrument including a base plate 1 having depending lugs 2 near opposite ends with pins 3 pivotally attaching pairs of legs 4 at the respective ends to support the base plate 1 in horizontal position as shown in the several figures. 15 Stop lugs 5 bear up against the lower surfaces of the base plate 1 to limit the outward swinging of the legs; or, as shown in Figure 2 by dotted lines, the legs 4 may be folded up under the plate 1 when the device is not in use or when it is laid on a 20 chart for scribing, as later will be described.

The plane top 6 of the base plate 1 has, near the left end of the machine, a longitudinal groove 7 along the middle of which runs a slot 8. The toe-spring plate 9 has a part 10 fitting the groove 7 and a tongue 11 fitting the slot 8; so that this toe-spring plate 9 is accurately guided longitudinally of the base plate 1. The toe-spring plate 9 is considerably wider than the groove 7, so that side portions 12 overlie and contact with the top 6 of the base plate, keeping the toe-spring plate 9 from tilting sidewise. This toe-spring plate 9 is triangular in longitudinal section, with its top 13 sloping down toward the opposite end of the machine. It has on this top 13 a longitudinal series of graduations 14 with indicia 15, to indicate the height of the top of the toe-spring plate 9 from the top of the base plate 1 at the respective graduations. Thus, when a last A is placed on the base plate 1 as shown in Figure 1, with its toe toward the plate 9, this plate 9, slid toward the last until its top 13 contacts with the tip 16 of the toe of the last without lifting the last from the base plate 1, the index of the graduation nearest this tip will indicate directly the toe-spring, i. e., the rise of the bottom of the last from its tread 17 that bears on the base plate, to the tip 16 of the last.

Near the right end of the base plate 1, and 50 near the edge 18 thereof, which will be called the front edge of the plate 1, a lug 19 having a transverse opening 20 depends from the lower surface of the plate. A clamp bolt 21 with a head 22 and a threaded end part 23 passes for- 55

ward through the opening 20, with the head 22 bearing against the back of the lug 19. The base plate 1 has its front edge 18 recessed at 19a to provide an offset.

- 5 A flat bar 24 fits in the recess 19a, has a longitudinal slot 25 and lies against the front of the lug 19 with the bolt 21 extending through the slot 25 and receiving the wing nut 26 whereby this bar may be clamped at any up and down 10 adjustment within the limits of the length of the slot 25, as well as at various inclinations. The recess 19a is long enough to permit such maximum degree of inclination as is required, as later will be described. This bar 24 has its upper end 15 part 27 bent to a horizontal position crosswise of the machine but preferably inclined down toward the left hand end of the machine as viewed in Figures 1, 2 and 3. Fixed on this end portion 27 is the shoe last heel support 28. This 20 heel support 28 is rectangular and has fixed on its front edge an upstanding grip piece 29, with a roughened and recessed surface with which the thumb of the user may make efficient contact while gripping the piece 29 between the 25 thumb and finger for moving the support 28 and its bar 24 when the nut 26 is loosened.

The flat top of this heel support 28 has a transverse slot 30 near its front end and, connecting with it and extending rearwardly therefrom on 30 the median line of the support, a second slot 31. In the front and rear end parts, respectively, of the transverse slot 30, and in the outer end part of the second slot 31, are guided the jaws 32, each with a step 32a. Screws 33 are 35 threaded through respective bushings 34 fixed in the front end of the transverse slot 30 and the outer end of the second slot 31, to bear against and adjust inward the jaws 32 in the respective slots 30 and 31. This adjustment accommodates lasts of different widths. At the rear 40 end of the transverse slot 30 is a bar 30a through which is threaded a screw 33a similarly related to the rear jaw 32. The front and end screws 33 have their heads extended out from the bushings 34, which also preferably extend past the edges of the support 28; but the rear screw 33a has a wide flat head 33' which does not extend past the rear edge of the block 28 at any 45 adjustment, lying within a recess 28a in the rear edge of the support 28.

Near the rear right hand corner of the top of the bed 1 is an index line 35 extending to the rear edge 18a of the bed and at right angles thereto.

I use as a part of my invention a protractor 55 comprising a plate 36 semicircular in its upper part 37 and rectangular in its lower part, which has a base part 38 turned at right angles to the above parts, with a plane bottom adapted to rest accurately on the plane top of the base plate 1. The beam 39 of this protractor, with 60 its pivot 49 concentric with the upper part 37 of the plate 36, has a short arm 41 extending from its pivot end part substantially radially to the pivot 40, with its end describing an arc 65 concentric with the pivot and having an index line 42 extending radially to this end. Near its top, the semicircular part 37 of the plate 36 has fixed on it a sector plate 43 with its inner edge describing an arc very closely to which the arc-shaped end of the beam arm 41 swings at certain 70 adjustments of the beam as will be described; and this sector plate has an arcuate series of 75 graduations 44 with indicia 45. The index line 42 thus may refer accurately to any one of these 75 graduations. The beam 39 has along one edge

a series of graduations 46, with indicia 47, from near its pivot 40 outward a sufficient distance. Aligned horizontally with the pivot 40, on the protractor plate 36, is an index line 42a at the left.

I also use as part of my invention, as shown in Fig. 6, a chart 48 having a horizontal base line 49 and a vertical positioning line 50 meeting the base line 49 at 51 near the right end thereof. Parallel with the base line 49, and succeeding 10 thereabove at equal intervals are lines or abscissas 52; and parallel with the vertical positioning line 50, and succeeding to the left therefrom at equal intervals are lines or ordinates 53. The abscissas and ordinates are provided with 15 respective indicia 54 and 55, respectively, starting from the point 51. The spacing, as well as the indicia, of the horizontal lines or abscissas 52, correspond to those of the graduations 46 on 20 the protractor beam 39; and for convenience, the spacing of the vertical lines or ordinates 53 is the same as that of the horizontal lines or abscissas 52 and the protractor beam graduations.

The protractor beam 39 is used in conjunction with the sector plate 43, as shown in Figure 2, for 25 gauging the wedge or slope of the heel; and is used when set perpendicular to the protractor base, as shown in Fig. 3, for gauging the height of the heel.

Operation.—To determine the height of heel, 30 degree of wedge of heel and toe spring of a last, the last A is placed on the machine as in Figure 1 with the heel part of the last resting on the steps 32a of the jaws 32 of the heel support 28, the jaws 32 being adjusted to position the last with its median longitudinal line coinciding substantially with the corresponding median longitudinal line of the machine and to position the last lengthwise of the machine. The heel of the last resting on the three jaws 32 places the heel seat of the 40 last in a plane parallel to the surface of the support 28 whereby the degree of wedge of the last heel seat may be determined by gauging the angularity of the support 28. The heel support 28 as a whole is adjusted vertically and angularly by 45 means of the bar 24 and clamping bolt 21 so that the last treads correctly on the base plate 1 at 17 and the heel portion of the last rests on all three steps 32a of the jaws 32. To gauge the toe-spring of the last, the plate 9 is moved toward 50 and in under the tip 16 of the toe of the last, the height of toe spring being read on the upper surface of the plate. To determine the degree of wedge of the last heel portion, the last is removed from the device and the protractor is placed as 55 shown in Fig. 2 with the protractor beam 39 set so that its edge coincides with the top of the heel support 28. This permits the degree of wedge of the heel to be read by means of the beam arm index line 42 and the graduation 44 nearest to this line on the protractor sector plate. Then, to gauge the height of the heel end of the last, the protractor beam 39 is swung vertical, which 60 position is determined by reference to the index line 42 on the beam arm 41 and the index line 42a on the protractor plate, and the protractor is placed, as seen in Fig. 3, alongside the rear edge of the heel support 28 and alongside the bar 35 with the protractor base resting on the base plate 1, and with the protractor beam edge that has 65 the graduations 46 disposed at the point on the machine to correspond with the point where the heel is to be measured for height. The beam graduation nearest the top edge of the heel support 70 then indicates the height of the heel. The last 75

may be placed on the machine for visualizing the location of the height measurement, as the heel block 28 is wider than the last.

To draft a heel to fit a given last, place the last on the machine as seen in Fig. 1, adjusting the heel support and its jaws, making the last tread correctly on the base plate 1, as before described. Remove the last from the machine and lay the machine with its rear edge 18a on the chart, with the heel support at the right end of the chart where the spaced lines 52 and 53 are; make the top of the rear edge 18a of the base plate 1 coincide with the base line 49 of the chart, with the index line 35 of the bed 1 coinciding with the vertical positioning line 50 of the chart. Draw a line 56 on the chart along the upper rear edge of the heel support which, by reading the indicia of the horizontal lines or abscissas 52 cut by the drawn line at the point of heel height, will give the heel height in terms of the chart. The line 56 thus drawn on the chart shows by its angle to the base line of the chart, the angle to which the heel base should be made. The outline 57 of the last is drawn on the chart by means of a last pattern, a variety of which is furnished with the machine for different heights of heel. In drawing this outline the heel base line 56 which was taken from the machine, is not disturbed. This last outline 57 enables the draftsman to visualize the shoe, thus having a better guide in drafting the heel. The placing of this last outline shows, in conjunction with the base line 49 of the chart, the angle of tread, as well as the toe spring. When the heel has been drafted on the chart, an opening cut in the chart on the heel outline will afford a template; and the piece thus cut out will afford a pattern. Such patterns and templates facilitate the making of the model heel by hand work, using a band saw to cut the general lines and surfaces.

For drafting a heel, with the measurements (Fig. 6) for pitch under p , length of top t , rake r , and length of base b predetermined, or specified, place the last on the machine and adjust as previously described, as to heel seat and tread and heel height desired. Remove the last and place the machine on the chart as before described, drawing the line 56. Lay the last pattern for a given heel height on the chart with back of heel of pattern on the vertical positioning line 50 of the chart and the heel seat portion of the pattern on the line 56 taken from the machine, and mark all around the pattern except this line 56; upon which the chart is ready for the draftsman who is to draft the heel, and who will, by light lines easy to erase, bring the heel outline on the chart to the style desired. A pattern and template then may be made by cutting the chart as above described. The chart 48 in Fig. 6 shows the angle of the line 56 with the base line 49, together with the factor of the length of heel base b of the heel that was called for, bringing the height of the heel between ordinates 15 and 16, from which results a height h of heel, since the line 56 cuts the front limit of the heel base between abscissas 13 and 14, which will be read $13\frac{1}{2}/8$, meaning thirteen and one-half eighths of an inch. In like manner the pitch under p is read $\frac{7}{8}$; the length of top t is read $16\frac{1}{8}-\frac{7}{8}=9\frac{1}{8}$; base b , $15\frac{1}{2}/8$ and the rake r is read $\frac{1}{16}$.

The heavy lines show a design 58 of a Cuban heel thus designed, and the dotted lines show a design 59 of a Louis heel thus designed. Both designs may be shown on the same chart, to the same measurements as indicated; the actual

drafting being done, for instance, in black for one design and in red for the other design. It will be seen that by using my method, which is greatly facilitated by the apparatus as disclosed, the necessary points and guide lines are placed on the chart for the easy guidance of the draftsman, with an accuracy and facility which is not attained by trying to take measurements from the variously curved last itself, directly, for beginning the construction lines of a drawing for the heel.

My apparatus is provided with many refinements of detail not essentially present in a device which is capable of affording the above advantages, and it is of course possible to proceed with means considerably varied from that disclosed. Also, the apparatus is subject to variations in practice which will not depart from the scope and spirit of my invention, as also is the method set forth.

Therefore, while I have set forth a preferred example of my invention, rather specifically as is required, I do not wish to be understood as being limited to such precise disclosure, but what I claim as new and desire to secure by Letters Patent, is:

1. In apparatus of the character described, a base element, a heel element adjustable to the heel base part of a last treading on the base element, and a protractor comprising a beam and a base to lie on said heel element and said base element, respectively, and comprising means for reading the angle of the heel element to the base element when said protractor beam and base have been adjusted to the heel element and base element after adjustment of the heel element to the last, and said protractor beam being adjustable to a position at right angles to the protractor base, and having indicia whereby, upon placing said protractor base on said base element with said beam upstanding alongside said heel element, height of heel of the last may be read by referring said beam indicia to an edge of the heel element.

2. In apparatus of the character described, a base element to be contacted by the tread of a last, a heel engaging element adjustable on the base element to various degrees of projection therefrom and to various angles with the base element at the various degrees of projection to engage the under side of the heel of said last, and means for gauging the projection and angle of said heel element to determine the height and angle of a heel to fit a shoe made on the last.

3. In apparatus of the character described, a base element to be contacted by the tread of a last, having a side edge free to bear on a surface for scribing a line along its edge on said surface, and a heel element adjustable on the base element to various degrees of projection therefrom and to various angles with the base element at the various degrees of projection, and having a side edge in the same plane as said side edge of the base element free to bear on said surface for scribing a line on said surface to record the height and angle of a heel to fit a shoe made on the last.

4. In a device of the character described, elements having adjacent edges free to be applied to a surface for scribing lines along said edges on the surface, and having surfaces corresponding with said edges, respectively, to contact the tread and the heel base portions of a last, and means connecting said elements together to vary the degree of projection of one element from the other and to vary the angle of one element to the other at

the various degrees of projection independently of the degree of projection, whereby the elements may be adjusted to the respective portions of the last for recording, by the lines scribed along said edges, the height and angle of a heel to fit a shoe made on the last.

5. In a device of the character described, a base element to contact the tread of a last, a heel element to contact the heel base portion of the last, and a connection between said elements permitting the heel element to slide on the base element and to swing to various positions on the base element in any one position into which it is slid thereon, to gauge the heel height and heel 10 angle of the last, and means to hold said connection in adjustment.

6. In a device of the character described, a base element to contact the tread of a last, a heel element angularly and bodily adjustable relatively to the base element, and spaced contact members on said heel element, adjustable there-across, each having a surface to contact a spaced edge portion of the bottom of the last within the heel base area thereof, and a surface to contact 25 a side portion of the last adjacent to said area, said base and heel elements having surfaces free to be applied to an indicating device, by which reference may be made for gauging the height and angle of a heel to fit a shoe made on the last.

30. 7. In a device of the character described, a base element to contact the tread of a last, and a heel element angularly and bodily adjustable relatively to the base element to contact the heel base portion of the last, said elements having 35 surfaces free to be applied to a heel height measuring device and by a heel angle measuring device, and adjacent edges free for contact with a plane surface for scribing lines along said edges on the plane surface.

40. 8. In apparatus of the character described, a base element, a heel element inclinable to and adjustable in its inclination to the heel base part

of a last treading on the base element, and a device for gauging the inclination of the heel element after removing the last from the apparatus, said device comprising relatively angularly adjustable parts contacting the respective elements, and also comprising means for indicating the degree of relative adjustment of the parts of said device, affording a quantitative expression of the inclination of the heel element and consequently of the inclination of the heel 10 base part of the last relative to the tread thereof. 5

9. In apparatus of the character described, a last tread support, a support for the heel end of the last carried by said tread support and adjustable angularly and vertically with relation thereto, whereby to coincide with the height and degree of wedge of the heel seat end of the last, and means for gauging the height and angularity of said heel seat support. 15

10. An apparatus of the character described, a last tread support, a support for the heel end of the last carried by said tread support and adjustable angularly and vertically with relation thereto, whereby to coincide with the height and degree of wedge of the heel seat end of the last, 20 and means for gauging the height and angularity of said heel seat support, said means including a measuring instrument coacting with said tread support and adapted to selectively determine the angularity and height of such support. 30

11. An apparatus of the character described, a last tread support, a support for the heel end of the last carried by said tread support and adjustable angularly and vertically with relation thereto, whereby to coincide with the height and 35 degree of wedge of the heel seat end of the last, and means for gauging the height and angularity of said heel seat support, and means carried by said tread support and coacting therewith to gauge the toe spring of the last. 40

GEORGE CLAUSING.
